UNITED STATES PATENT OFFICE.

OSCAR SCHWIMMER, OF LOS ANGELES, CALIFORNIA, ASSIGNOR TO PATENT PRODUCTS COMPANY, OF LOS ANGELES, CALIFORNIA, A CORPORATION OF CALIFORNIA.

TOWEL-MACHINE.

1,386,369.

Specification of Letters Patent.

Patented Aug. 2, 1921.

Application filed November 4, 1919. Serial No. 335,759.

To all whom it may concern:

Be it known that I, OSCAR SCHWIMMER, a citizen of the United States, residing at Los Angeles, county of Los Angeles, and 5 State of California, have invented a certain new and useful Improvement in Towel-Machines, of which the following is a specification.

This invention relates to a means for dispensing toweling and contemplates an advancement in several of those types of machines heretofore patented to me and involving generally the idea of paying out from a roll of toweling a determinate length governable by the operation of a lever.

I have found that in a great many instances, the lever is pressed down with such force that undue acceleration of the rollers occurs, causing a disarrangement and entanglement of the clean with the soiled toweling and necessitating at least partwise dismantling of the machine parts to straighten out the toweling.

This invention therefore has in view to obviate this difficulty by a simple means which will make constant and uniform each unwinding of a determinate length of toweling; to provide a machine in which the extent of the loop exposed for use never varies; 30 in which the take-up roller winds up exactly as much toweling as is unwound from the supply spool; to provide a simplified arrangement of mechanism to economize space, and in which, under no condition of disorder 35 or disarrangement, the soiled toweling may come in contact with the clean toweling or become entangled.

Other advantages, objects and features will appear from the subjoined specification 40 in connection with the accompanying drawings, representing a preferred form of embodiment of the invention, and in which—

Figure 1 is a plan view showing the four rollers and the operating mechanism therefor.

Fig. 2 is a side view looking from the left of Fig. 1.

Fig. 3 is a side view looking from the right of Fig. 1, one wall of the case being 50 omitted.

Fig. 4 is a fragmentary front view of the toweling supply roller showing the braking arrangement.

Fig. 5 is a fragmentary plan view of Fig. 4.

Fig. 6 is a fragmentary front view of the 5 operating mechanism for the rollers.

Fig. 7 is a fragmentary front view of the take-up roller and the actuating mechanism therefor, and

Fig. 8 is a fragmentary view of the take-up roller showing the axle thereof provided with a plane surface.

Referring in detail to the drawings, especially to Fig. 3, the toweling 1 is wound upon a spool or roller 2, journaled in suitable brackets 3, that are secured to the back 4 of a case 5. The free rotation of the roller 2 is prevented, and the consequent unwinding of more than a determinate length of toweling, may be controlled by a frictional 70 means, as a brake shoe 6, secured to a spring 7, which is fastened to one of the brackets 3, and which shoe bears against one end of the spool 2.

Below said toweling supply spool 2, is a 75 plurality of spaced frames 8, also secured to said back 4. In these frames are journaled the axles 9 and 10, and 11 and 12, of four horizontally disposed rollers 9' and 10', and 11' and 12', the axle 9 extending in transverse slots 13 in the rear of said frames, and the axles 11 and 12 extending in transverse slots 14 in the front of said frames.

Connecting with the axles 9 and 12 are spring pressed means 15 for holding the 85 roller or spool 9' in such firm engagement with the spool 10', and for holding the spool 12' in such firm engagement with the spool 11', that the toweling passing between these respective pairs of rollers is advanced solely 90 by the revolution of them and is securely held by them against slippage. In this wise, the extent of the loop A on the outside of the case is held constant and the take-up roller, hereinafter described, operated in such manner that equally as much toweling is wound up thereby, as is unwound from the supply spool, regardless of the diametrical increase 95 of the toweling thereon, and only by such gripping of the toweling by the rollers is this possible, since thereby the slipping of the take-up roller operating belt is made positive. At the same time, such spring pressed means enables the rollers to respond

to the many irregularities existing in the 105 toweling 1, that is drawn between said rollers. The rollers 9' and 11' are provided with flanges 16 and 17, respectively, to hold

- the toweling in place, and the rollers 9' and 10' are spaced from the rollers 11' and 12', at all times to prevent contact of the soiled with the clean toweling, which runs between, and 5 is drawn from the supply roller, by the rollers 11' and 12'; thence emerges from the case; is returned through an opening 18 in the bottom of the case to within the same; passes upwardly between the rollers 9' and 10'; downwardly between the spaced sets of rollers, and finally is wound upon a take-up roller 19, the axle 20 of which is journaled at one end in the slotway 21 of a bracket 22, and the other end of which is removably 10 connected with a driving mechanism herein-after described. As seen, sufficient slack is left in the toweling outside of the case for convenient and free use of each clean extent of toweling as it is exposed.
- 20 On one end of the axles 9 and 10 are mounted intermeshing gears 23 and 24, respectively, and on one end of the axles 11 and 12 are mounted intermeshing gears 25 and 26, respectively, the gears 24 and 25 25 meshing with an idler gear 27, journaled in one of the frames and provided to produce a motion of the rollers 11' and 12' reverse to that of the rollers 9' and 10'.
- On the axle 10 is mounted a pinion 28, 30 which meshes with a gear wheel 29 loosely mounted on a spindle 30 secured in and extending from the frame. This gear wheel 29 is provided with a plurality of spring pressed pawls 31 and 32, coöperating with 35 a ratchet crank 33, removably fitted on said spindle, and which, when moved in one direction, engages said pawls 31 and 32 and causes the gear wheel 29 to be moved with the crank. When moving the crank in the 40 opposite direction, the pawls 31 and 32 slide over the ratchet teeth of the crank, which is normally under the tension of a spring 34. The hub 33' of said crank is provided with a pin 35, for engagement 45 with a stop arm 36, projecting from the frame to limit the movement of the crank to one revolution. Further to limit the movement of said crank in order to regulate the presentation for use of a definite 50 length of toweling, the frame may be provided with a hole 37 for accommodation of another stop arm, not shown, complementary to the stop arm 36, and obviously a number of such holes may be provided for still further limiting the crank movement. The crank hub 33' is formed with a groove 55 38 for a split washer 39, Fig. 6, which prevents dissociation of the crank from the spindle 30. For convenience of threading the toweling, each of the rollers 9' and 11', and the take-up roller 19 may be provided with a stud 40, 41 and 42, respectively, onto which a ring 43 or other device, secured to the end of the toweling may be placed.
- 60 On the other end of the axle 10 of the 65

master roller 10' is a fixed a sheave 44 connected with a means, presently described, for operating the take-up roller 19, by a spring belt 45.

Oppositely disposed relatively to the 70 bracket 22, is a complementary bracket 46, secured to the back 4 of the case. This bracket 46 is provided with a member 47, constituting with the bracket a bearing for a hollow journal 48, formed with a plane 75 surface, not shown, to accommodate the similarly shaped other end 49 of the axle 20 of the take-up roller 19. Fixed on said journal 48, is a sheave 50, over which runs the spring belt 45, aforementioned, through 80 which motion is communicated from the master roller to the take-up roller, and to which sheave 50 is connected a ratchet wheel 51, with which coöperates a pawl 52, to prevent the unwinding of the toweling 85 on the take-up roller. As will be seen from Fig. 7, the operating mechanism for the take-up roller is permanently fixed in position, so that the take-up roller may be removed without disturbing such mechanism 90 or disconnecting any of its complementary parts.

To facilitate the placement of and hold the axle of the take-up roller 19, in the slot-way of the bracket 22, a latch 53 may be 95 provided. This latch is pivotally mounted on the bracket 22 and is formed with an arcuate portion 54, conforming approximately to the contour of the axle and arranged to fit over the axle and hold the 100 same in place. The latch is normally under the tension of a spring 55, which holds same against a lug 56 on the bracket. The latch is also formed with an inclined portion 57, whereby, pressure being exerted thereagainst by the axle during the act of insertion thereof, the latch will rise and thus permit the axle to slide into said arcuate portion. In this wise the manual operation of locking the roller in place is 105 110 eliminated.

The toweling being properly threaded, it will be apparent that, as the crank is turned in a direction that will cause the pawls to engage the ratchet teeth of the crank, the rollers 11' and 12' will be revolved, thereby drawing from the supply spool 2 a length of toweling, which emerges from the case for use and is then simultaneously drawn into the case by the rollers 9' and 10'. At 115 the same time, the take-up roller 19 is revolved by the means herein described, which controls the revolution thereof rotatably with the diametrical increase of the soiled toweling.

One of the chief advantages of the crank control as stated hereinbefore, is to produce a slower and uniform motion and fore-stalling acceleration of the various rollers whereby the toweling is always evenly drawn 125 130

through and the motion of the take-up roller equalized.

What I claim, is:—

A toweling dispensing means comprising
5 a case having an opening in the front for
advancing toweling therethrough and an
opening in the bottom at the rear for the
withdrawal of toweling; a frictionally held
toweling supply roller in said case, a plu-
10 rality of pairs of rollers journaled in said
case, the pairs of rollers being spaced from
each other, one pair of rollers serving to
draw toweling from the supply spool and
pass the same for use outside of the case,
15 and another pair serving to return used
toweling to within the casing, said rollers

being provided with intermeshing gearing
so that all of said rollers are geared together,
a pinion on one of said rollers, a gear mesh-
ing with said pinion, a hand crank for op-
erating said gear secured thereto by one di-
rection clutch means, means to limit the ro-
tation of said crank in both directions, a
take-up roller, means to operate said take-
up roller, and a yielding means connecting 25
said operating means for said take-up
roller with one of said returning rollers to
operate said take-up roller simultaneously
with said feeding and returning rollers.

In testimony whereof I have set my hand. 30

OSCAR SCHWIMMER.
